LOADBREAK DEVICES FOR HOUSED CUTOUTS

Ralph H. Earle, Wauwatosa, Wis., assignor to McGraw-Edison Company, Milwaukee, Wis., a corporation of Delaware

Application June 16, 1958, Serial No. 742,317

4 Claims. (Cl. 200—114)

This invention relates to loadbreak devices for housed cutouts.

In certain loadbreak devices for housed cutouts, as heretofore constructed, the loadbreak device is mounted in such a manner that it discharges in the direction of the operator when he opens the door of the housed cutout, thus endangering the safety of the operator.

Further than this, in loadbreak devices of this general type it has been necessary to make special housings and to change other parts of the device so that a standard type of cutout could not be used with the loadbreak device itself.

This invention is designed to overcome the above noted defects and an object of this invention is to provide a loadbreak device which is so constructed that it may be used with a standard housed cutout without requiring any change whatsoever in the main body of the housing, and only requiring a special door which may be substituted for the usual or conventional door of the housed cutout. In housed fuse cutouts it is the usual practice to provide a porcelain housing or other type of ceramic housing and to provide a "Bakelite" or other type of plastic removable door, and therefore this invention may be readily applied to such construction in that the conventional door may be removed and replaced by the new door with the loadbreak device.

A further and specific object of this invention is to provide a construction of loadbreak device for any of the usual types of housed cutouts such as housed drop-out fuses for example, which is so made that the door may readily be substituted for the conventional door of a housed fuse or for other types of cutout while still retaining all of the usual advantages of the conventional cutout.

A further object is to provide a door construction for a housed fuse cutout in which the loadbreak device is formed as a unitary portion of the door so that the door may be opened under load by hand or by a switch stick and to so construct and position the loadbreak device that the blast from it is directed away from the face of the operator when he opens the door under load.

A further object is to provide a construction which is eminently practical and which may be easily made and which has a minimum number of parts all of which are sturdy and reliable.

Embodiments of the invention are shown in the accompanying drawings, in which:

Figure 1 is a sectional view showing a housed fuse cutout with the door in closed position.

Figure 2 is a fragmentary sectional view showing the door in partially open position.

Figure 3 is a fragmentary view showing a further form of loadbreak device.

Referring to the drawings, particularly Figures 1 and 2, it will be seen that the device is adapted to be used with an ordinary type of housed cutout.

The housed cutout is provided within a housing 1, usually of porcelain, which has upper and lower contacts

2

indicated generally by the reference characters 2 and 3. The housing is adapted to removably receive the ordinary "Bakelite" or plastic door, not shown, and the present invention provides a special door 4 which replaces the ordinary door for the common type of housed cutouts.

The door 4 carries a fuse tube which may be slidably or otherwise supported from the door. The fuse structure indicated generally by the reference character 5, includes the fuse tube 6. The fuse tube 6 may be of the usual type except for the special metallic cap or top portion 7. The cap 7 is screwed on the tube 6 in the usual manner and is provided with a cylindrical portion 8 of reduced diameter.

The door 4 is provided with the usual eyelet or member 9 which is adapted to receive the finger of an operator or a switch stick so that it may be manually opened or closed when desired.

This invention is designed to provide a special form of door which has a loadbreak device forming a portion thereof and so constructed that the door may be pulled open while the housed cutout is carrying a load, without damage to the upper contacts of either the housing or fuse tube, since the separation or break in the circuit occurs within a cylindrical portion of the special door 4.

25 This cylindrical extension or portion 10 is provided with a fiber tube 11 which is screwed into an arcing electrode 12 carried within the tubular portion 10. The tubular portion 10 is provided with an enlarged cylindrical chamber 13 and with a smaller cylindrical chamber

30 14. The fiber tube 11 is positioned within the tubular portion 10 of the loadbreak device, and is provided with a screw threaded portion 15 which, as stated above, is screwed into the arcing contact or electrode 12. The arcing electrode 12 may be of brass or other conducting material. The arcing electrode 12 is removably carried

35 within the intermediate portion 16 and is held in place by means of an externally threaded spanner nut 17 which is screwed into the threaded portion 18 of the cylindrical housing or extension 10 and holds the removable arcing

40 electrode 12 in place. Between the nut 17 and the electrode 12 a right angled portion 19 of a conductor and contact finger 20 is positioned and is held in clamped relation to the arcing electrode 12. The finger 20 may be of spring brass or other material and contacts the

45 metallic top or cap 7 of the fuse tube 6 and is apertured as indicated at 21 and fits over or receives the reduced cylindrical extension 8 formed integrally with the cap 7. The finger 20 also acts as a means for withdrawing or

50 as it pulls directly against the top cap of the fuse tube and carries the fuse tube outwardly when the door is

rocked outwardly.

The upper stationary contact 2 of the housing is provided with a U-shaped spring finger 22 whose lower

55 portion is bent rearwardly, as shown, and directly contacts the top of the reduced portion 8 of the metal cap

7 of the fuse tube under normal conditions.

An alnico magnet or contact member 23 is removably clipped or fastened to the stationary upper contact

60 of the housing by any suitable means as for example the clip 24 so that it may be added to a conventional housed fuse structure by merely clipping it on to the upper contact of the housing.

One of the main portions of the loadbreak device includes the slidable plunger formed of the conducting metal rod or plunger portion 25 which may be of brass or other suitable material, and the rearward or outward extension 26 of suitable insulating material such as "Lucite" for example. This "Lucite" plunger 26 is secured in any suitable manner to the outer or rear end of the brass rod 25. The rear end of the "Lucite" plunger

70 26 is provided with a rigidly attached collar 27 which

may be of metal or may be formed of plastic as an integral portion of the plunger 26.

The composite plunger 25, 26 is provided with an alnico magnetic rounded terminal or magnetic contact portion 28 which engages the magnetic member 23 and thus holds the slideable rod or slideable plunger 25, 26 in place under normal conditions and with the magnetic portions 23 and 28 in contact with each other thus forming a conducting path for the current from the upper stationary contact 2 of the housing through the brass rod portion 25 of the plunger to the arcing contact 12 of the loadbreak device and from there to the spring finger or contact finger 20 which engages the upper metal cap of the fuse tube. It will be seen therefore that when the door is closed or in other words when the device is in normal operative position there are two paths arranged in shunt or parallel; one of them from the upper contact directly to the upper cap 7 of the fuse tube and the other from the upper contact 2 of the housing through the contact members or magnetic portions 23 and 28 through the brass rod 25, through the finger 20 to the upper metal cap 7 of the fuse tube. The current then flows through the fuse link, not shown, to the lower stationary contact of the housing.

The operation of the apparatus is as follows: When it is desired to open the circuit under load it is merely necessary for the operator to pull the door open by engaging the finger or eyelet 9 of the door with his finger or with the end of a switch stick. When the door is rocked outwardly, the plunger 25, 26 stays in its original position except that it rocks in an angular manner due to the rotation of the door at its lower hinge or supporting structure 29. This outward motion of the door continues with the two parallel or shunt circuits both intact as described hereinabove, until the upper contact or movable contact 7 of the fuse tube passes beyond engagement with the upper stationary contact finger 22 of the upper stationary contact 2 of the housing.

However, continued rocking of the door outwardly, causes the contact rod 25 of the composite plunger 25, 26 to pass beyond or out of contact with the arcing contact or electrode 12. At this time the circuit is broken within the tubular portion 10 and this interruption produces an arc which immediately causes the cylindrical portion 14 to be filled with pressure gas. This increases the outward speed of the rod 25 of the plunger rod 25, 26 with reference to the cylindrical portion 10 of the door. The arc is quickly extinguished due to the pressure gas in the chamber 14 and also due to the outward blast of the gas past the arcing electrode.

The composite plunger rod 25, 26 has a loose fit with the cylindrical tubular sleeve or member 11 and the gas is free to pass through this restricted area between the rod and the fiber tube 11. If desired the tubular portion 14 may be provided with a vent or vents to prevent excessive pressure being built up so as to guard against bursting of the tubular cylindrical portion 14. The vents are not shown in the figures.

The relative motion of the composite rod 25, 26 with respect to the door continues until the shoulder or flange 27 abuts the arcing contact 12 and arrests further outward motion of the composite plunger or rod 25, 26 with reference to the tubular member 10.

When the device is put back into operation and the door closed, it is to be noted that the composite rod 25, 26 will drop backward, or in other words downward, into the tubular member 10 to its initial position. If desired a spring may be provided to assist in retracting or repositioning the composite rod 25, 26. The spring is shown at 31 in Figure 3. The spring 31 is partly housed within a recessed portion 32 of the "Lucite" plunger 26 and partly housed within a recessed portion of the extension 33 of the tubular member 10'. The ends of the spring may be fastened to the "Lucite" rod 26 and to

the extension 33 in any suitable manner for example by means of transverse pins.

It is to be understood that either one or both of the members 23 and 28 may be formed of alnico magnetic material and the other of soft iron.

It is further to be understood that minor changes may be made in the structure of the loadbreak device without departing from the spirit of this invention. Therefore, although the invention has been described in considerable detail it is to be understood that such description is intended as illustrative and not as limiting, as the invention may be variously embodied and is to be interpreted as claimed.

I claim:

1. A loadbreak device comprising a housing, a door pivoted at the lower portion thereof on said housing, said housing having contacts including an upper stationary contact, a fuse tube supported from said door and movable outwardly as a unit with said door when said door is rocked outwardly, said fuse tube having an upper contact cap normally in contact with the upper stationary contact of said housing, a load-break device carried as a unitary portion with said door and having a cylindrical portion provided with an open discharge end directed inwardly of the housing and away from the front of the door, a composite plunger slideable in said cylindrical portion and having an outer portion of insulating material and an inner portion of metal, the upper stationary contact of said housing and the outer end of the metal portion of said plunger having magnetic members normally in contact with each other, at least one of said magnetic members being a permanent magnet, and one of said magnetic members having a rounded face in contact with the opposed face of the other magnetic member whereby when said door is rocked outwardly, the rounded face of one of said magnetic members will roll upon the face of the other magnetic member as the angularity of the door with reference to the housing changes due to its rocking outward motion, said loadbreak device including a fixed contact in the cylindrical portion, and connecting means electrically joining the metallic portion of said composite plunger to the upper conducting cap of said fuse tube, whereby when said door is rocked outwardly beyond a predetermined point the upper metal cap of the fuse tube passes out of contact with the stationary upper contact of said housing and thereafter the metallic portion of the composite plunger passes out of contact with the fixed contact of the loadbreak device.

2. A loadbreak device comprising a housing having contacts one of which is an upper stationary contact, a removable magnetic member detachably carried by the upper stationary contact, said magnetic member having attraction only and acting solely as a temporary holding magnet, a door pivoted on said housing and rockable outwardly therefrom, a fuse tube carried by said door and having an upper contact normally in contact with the upper stationary contact of said housing, a loadbreak device carried as a unitary portion of said door and bridged between said upper stationary contact and the upper contact of said fuse tube, said loadbreak device being positioned to open after the upper contact of said fuse tube has moved away from the upper stationary contact of said housing.

3. A loadbreak device comprising a housing having a stationary upper contact, a door pivotally mounted on said housing, a fuse tube carried as a unitary portion of said door and having an upper contact normally in engagement with the upper stationary contact, a loadbreak device carried as a unitary portion of said door and rockable outwardly as a unit with said door, said loadbreak device being connected in shunt between the upper stationary contact and the upper contact of said fuse tube and arranged to open the circuit after the upper contact of the fuse tube has moved away from the upper stationary contact, said loadbreak device including a movable

actuating member, a removable magnetic member detachably carried by the upper stationary contact of said housing, the movable actuating member having a magnetic member normally in engagement with the removable magnetic member carried by the upper stationary contact, both of the magnetic members having attraction only, at least one of said magnetic members being a permanent magnet.

4. A loadbreak device comprising a housing having a stationary upper contact, a door pivotally mounted on said housing, a fuse tube carried as a unitary portion of said door and having an upper contact normally in engagement with the upper stationary contact, a loadbreak device carried as a unitary portion of said door and rockable outwardly as a unit with said door, said loadbreak device being connected in shunt between the upper stationary contact and the upper contact of said fuse tube and arranged to open the circuit after the upper contact of the fuse tube has moved away from the upper stationary contact.

10

15

tact, said loadbreak device including a movable actuating member, a removable magnetic member detachably carried by the upper stationary contact of said housing, the movable actuating member having a magnetic member normally in engagement with the removable magnetic member carried by the upper stationary contact, at least one of said magnetic members being a permanent magnet, one of said magnetic members having a flat face and the other of said magnetic members having a rounded face normally in contact with said flat face to accommodate the angular shifting of the movable portion of said loadbreak device as the door is rocked outwardly to open position.
